UNITED STATES PATENT OFFICE.

JOHN STAGGS, OF WASHINGTON, DISTRICT OF COLUMBIA, ASSIGNOR OF ONE-EIGHTH
TO THAD. E. RAGSDALE, OF WASHINGTON, DISTRICT OF COLUMBIA.

FASTENER.

1,067,281.

Specification of Letters Patent. Patented July 15, 1913.

Application filed February 3, 1912. Serial No. 675,268.

To all whom it may concern:

Be it known that I, JOHN STAGGS, a citizen of the United States, residing at Washington, in the District of Columbia, have invented certain new and useful Improvements in Fasteners, of which the following is a specification, reference being had therein to the accompanying drawings.

This invention provides a fastener that 10 will reliably hold two meeting parts or portions of an article together, and that will not unduly distend and eventually misshape a buttonhole or slot with which it co-operates.

The fastener is particularly adapted for 15 use on leggings and other articles made of leather or other comparatively stiff material.

When read in connection with the description herein, the details of the invention will 20 be apparent from the accompanying drawings, forming part hereof, wherein embodiments of the invention are shown in detail and as applied to a legging, for purposes of illustration.

25 While the embodiments of the invention shown herein are preferred, as they have given satisfactory results in practice, it is to be understood that it is not the intention to be necessarily confined thereto in interpretation of claims hereinafter, as changes in the forms shown can be made within the limits of the claims, without departing from the nature and spirit of the invention.

Like reference-characters refer to corresponding parts in the views of the drawings, of which—

Figure 1 is a side view of one form; Fig. 2 is a top view thereof; Fig. 3 is an end view thereof; Fig. 4 is an end view of another form; Fig. 5 is a top view of still another form; Fig. 6 is an end view thereof; Fig. 7 is a view of a legging equipped with the fastener and in position for the button-hole to be brought over the fastener; and 45 Fig. 8 is a view of the legging fastened.

Referring more particularly to the drawings, 12 designates the base of the fastener, which may be of any suitable form such as a plate as shown.

50 In the forms shown by Figs. 1 to 6, inclusive, the fastener includes a somewhat elongated retaining portion formed of a substantially rectangular loop, of wire-like rigid material, upstanding from, and with 55 its ends soldered to, the base, the loop consisting of uprights 13 and a cross-bar 14

substantially parallel to the base. The invention contemplates the shaping of the parts in such manner that the cross-bar 14 and the bends or corners 15 between the bar and the uprights 13, or the outer edge and corners of the sheet material, will be deflected from a perpendicular plane in which the junctions of the uprights, or of the lower edge of the sheet material, and the base lie, 60 in order that a button-hole or slot so formed in comparatively stiff sheet material that it lies normally in the same line as the junctions of the retaining portions with the base will be held on the fastener by the deflected parts. Figs. 1, 2, and 3 show the uprights 13 continuously deflected straight from the base, one to the right and one to the left; Fig. 4 shows the uprights continuously curved from the 65 base in direction of deflection to the bends 15; and Figs. 5 and 6 show only one upright deflected, the other upright being substantially at right angles to the base. It is to be understood, of course, that in the form 70 75 80 85 90 95 100 105 110

exemplified by Figs. 5 and 6 the one upright that is deflected may be curved as shown in Fig. 4. It will be seen that in all of these forms the cross-bar portion or outer edge and the bends connecting that portion to the uprights are deflected from position over the junctions of the uprights with the base; and that the stiffness of the material on which the fastener is used will prevent the distortion of the buttonhole or slot necessary to detach the same from the fastener, it being necessary to bodily "twist" the material, as shown by Fig. 7, to make or break the fastening.

In all the forms of the invention shown herein, in which the outer portion of the retaining part of the fastener is deflected from the line of junction of the retaining parts with the base, the configuration is such that there are no lateral projections 100 from a line or plane drawn from one point of deflection to another point of the retaining part. It will thus be seen that, when the material having a buttonhole or slot therein is "twisted" to bring the button-hole or slot in line with the cross-bar or outer edge of the fastener, it may be passed thereover and gradually returned to its normal position as it is passed down toward the base, without being subject to distortion by 105 any laterally-projecting parts as is the case with many forms of fasteners that grad-

ually wear buttonholes or their equivalents until they are useless.

The application of the fastener to an article is illustrated by Figs. 7 and 8, where-
5 in 20 designates the body portion of a leg-
ging, which when fastened has its meeting
portions lapped in the usual manner. The
overlapping portion has therein a button-
hole or slot 21, and the fastener is attached
10 to the lapped portion in a position to coöp-
erate with the buttonhole or slot to hold the
legging fastened. The buttonhole or slot is
disposed so that it will normally lie in a
line coincident with the line of junction be-
15 tween the base and retaining portion of the
fastener and out of line with the cross-bar
or outer edge when the parts are lapped.
When it is desired to bring the buttonhole
20 or slot into engagement with the fastener
to hold the parts together, the portion of the
article having the buttonhole or slot therein
is turned or twisted to bring the latter in
line with the cross-bar or outer edge, as
25 shown by Fig. 7, and then the buttonhole
or slot is easily passed thereover and the
material pressed toward the base to the pos-
ition shown by Fig. 8, during which move-
ment the material will be turned gradually
30 back to its normal position and the button-
hole or slot will not be subject to distortion
by contact with lateral projections. The
parts are disconnected by reversing this
movement.

It is necessary to make the buttonhole or
35 slot only a little, if any, longer than the
length of the cross-bar or outer edge of the
retaining portion of the fastener, because
of the fact that that portion is devoid of
any projections that will widen the button-
40 hole or slot when passing onto or from the
fastener.

By the use of this fastener, a legging may
be formed with a strap that extends only
45 from a place intermediate the top and bot-
tom to the bottom or top, the function of
one of the usual extensions to both top and
bottom being performed by the fastener.
For example, if the fastener is located near
50 the top, as shown by Figs. 7 and 8, a strap
22 is attached at one end to the lapping por-
tion near the bottom and brought around
the legging to a buckle or the like 23 at-
tached to the lapped portion about midway
55 between the top and bottom, whereby the
lower portions of the legging are held to-
gether, and the upper portions are held in
place by the fastener. Of course, a plurality
of buttonholes or slots may be formed in the
lapping portion, if desired, to permit adjust-
60 ment of the legging to legs of different sizes.

It is preferable that the fastener be so
placed on the legging that, when parts of
the legging distant from the fastener are

drawn together after the latter has been en-
gaged by the buttonhole or slot, the result-
ing twist in the material shall be in a direc-
tion opposed to the direction of deflection
65 of the retaining portion of the fastener, in
order that the material around the button-
hole or slot shall be turned under the de-
flected parts, rather than from under them
70 as would be the case if the deflection was in
the opposed direction. For example, if the
fastener is placed near the top of the leg-
ging, as in Figs. 7 and 8, the line of the
75 cross-bar or outer edge of the retaining por-
tion should slope downwardly away from
the outer edge of the lapped portion of the
legging, in order that, when the lower parts
80 of the legging are drawn together by the
strap, the twist shall be in a direction op-
posed to the angle of the cross-bar or outer
edge and the material around the buttonhole
85 or slot given an increased tendency to re-
main under the deflected portions of the
fastener. In other words, it is preferable
that the twist incident to turning the but-
tonhole or slot toward the base of the fas-
90 tener should be the same that is incident to
drawing the other parts of the legging to-
gether.

The uprights 13 may be roughened or cor-
rugated, if desired, to increase the retentive
power of those parts.

Having thus described my invention, what
95 I claim as new, and desire to secure by Let-
ters Patent, is—

1. A fastener comprising a base, and a
retaining portion of wire-like material bent
100 to form a somewhat elongated substantially
rectangular loop having uprights secured to
the base and a cross-bar joining the up-
rights, one of the uprights being deflected
continuously from the plane perpendicular
105 to the base and passing through the up-
rights as it rises from the base, whereby the
cross-bar is placed at an angle to said per-
pendicular plane.

2. A fastener comprising a base, and a re-
taining portion of wire-like material bent
110 to form a somewhat elongated substantially
rectangular loop having uprights secured to
the base and a cross-bar joining the up-
rights, one of the uprights being deflected in
one direction and the other upright in the
115 opposite direction continuously from the
plane perpendicular to the base and passing
through the uprights as it rises from the
base, whereby the cross-bar is placed at an
angle to said perpendicular plane.

In testimony whereof I affix my signature
in presence of two witnesses.

JOHN STAGGS.
